CLAIM

The ornamental design for a knife, as shown and described.

DESCRIPTION

FIG. 1 is a top plan view of the knife showing my new design, the main components being the blade arrangement, frame, grip and cuff;

FIG. 2 is a rear elevation view;

FIG. 3 is a side elevation view, the opposite side being a mirror image thereof;

FIG. 4 is a front elevation view; and,

FIG. 5 is a bottom plan view.

The shaded areas of the grip and cuff liner are for illustrative purposes and form no part of the claimed design.
